W. H. HARRISON, OF PHILADELPHIA, PENNSYLVANIA.

Letters Patent No. 98,961, dated January 18, 1870.

IMPROVEMENT IN CONNECTIONS FOR PIPES OF MALLEABLE METAL.

The Schedule referred to in these Letters Patent and making part of the same.

I, W. H. HARRISON, of Philadelphia, Pennsylvania, have invented an Improvement in Securing Pipes of Malleable Metal together, of which the following is a specification.

Nature and Object of the Invention.

My invention consists of two or more pipes of malleable metal, flattened at and near the ends, and adapted and secured to internal castings, and having countersunk openings, adapted to connecting-pipes, all substantially as described hereafter.

Description of the Accompanying Drawing.

Figure 1, a view, (partly in section,) representing two tubes, secured together according to my improvement;

Figure 2, a section on the line 1-2, fig. 1;

Figure 3, a sectional plan, on the line 3-4, fig. 2; and

Figure 4, a section, showing the interior casting and external flattened tube, prior to the upsetting of the latter.

General Description.

A represents part of an ordinary lap-welded tube, flattened at and near the end, on opposite sides, so as to have the sectional form represented in fig. 4, and two holes, *a a*, are bored, one through each flattened side of the tube.

B is a hollow casting, flat on opposite sides, and rounded on the opposite edges, so as to conform to and fit snugly in the interior of the flattened end of the tube A; and this casting has holes, *b b*, of the same size, or nearly so, as the holes *a a* in the tube, and coinciding with the latter when the casing is fitted to its place.

The tube A is connected to the casting B by any desired number of bolts or rivets *d d*, each of which passes through a stay, *e*, forming part of the casting, and connecting together the opposite sides of the same.

Each hole *b* of the casting B is countersunk, so as to form a concave edge, *x*, into which the metal of the tube A, at the edge of the opening, is upset, as shown in fig. 3, and the metal thus upset is countersunk, so as to form a concave edge, fig. 3.

A number of tubes thus prepared, with flattened ends and internal castings, may be connected together, as shown in fig. 1, where D represents the connecting-

pipe between two tubes A and A', this pipe being made convex at each end *m*, one convex end being adapted to the concave edge *y* of the opening in the tube A, and the other end of the pipe to the concave edge of the opening in the tube A'.

The desired number of tubes A and A' having been arranged side by side, with intervening connecting-pipes D, the whole are connected together by a bolt, E, passing through the pipes D, and through the holes in the tubes, each end tube A of the series having a washer, *f*, adapted to the bevelled edge *y* of the hole in the tube.

In the present instance, the casting B projects beyond the end of the tube A, the projecting portion being rounded, as shown in fig. 1, and having two openings, *h h*, in each of which is cut a screw-thread, for receiving a screw-plug. These openings possess the double advantage of facilitating the preparation of the moulds for the castings B, and of permitting ready access to the tubes for cleansing-purposes.

A number of tubes may be connected together, in the manner described above, so as to form a steam-boiler or heater; and, as the junction of all the pipes is by ball-and-socket joints, (owing to the convex ends of the pipes, D, and the concave edges *y* of the openings in the tubes,) liberty is afforded for the free and independent contraction and expansion of the parts, without affecting the integrity of the joints.

In some cases, the edges *y* of the openings in the tubes may be simply bevelled or inclined, the ends of the connecting-pipes being bevelled accordingly; but I prefer, in most cases, to make the joints of a ball-and-socket character, for the reasons given above.

Claim.

Two or more pipes, A and A', of malleable metal, flattened at and near the ends, and adapted and secured to internal castings B, and having countersunk openings, adapted to connecting-pipes D, all substantially as set forth.

In testimony whereof, I have signed my name to this specification, in the presence of two subscribing witnesses.

W. H. HARRISON.
